FUEL-COOLANT SYSTEM

Nelson M. Jones, Sarasota, Fla.

Application July 16, 1942, Serial No. 451,201

2 Claims. (Cl. 123—133)

This invention relates to a system wherein an internal combustion engine is cooled by the passage of fuel from the liquid to the vapor state, and particularly such as liquid petroleum gases and usually butane, or propane.

A particular object of the present invention is to provide an effective system or means of the flooded type wherein a predetermined quantity of the fuel is maintained within a cylinder jacket of the engine and vapor from such fuel above the predetermined level passes to the mixing valve.

It is also aimed to provide in combination effective means to control the aforesaid predetermined fuel liquid level as by means of a thermostatically actuated inlet valve or a float control inlet valve.

Various additional objects and advantages will become apparent from a consideration of the description following taken in connection with accompanying drawings illustrating operative embodiments.

In said drawings:

Figure 1 is a view in central vertical section, primarily, through an engine embodying my improvements;

Figure 2 is an enlarged central vertical section through the mixing valve;

Figure 3 is a central vertical section through a modified form of the invention, and

Figure 4 is a horizontal section particularly showing the float control inlet valve.

Referring specifically to the drawings wherein reference characters designate like or similar parts and first to the form of Figures 1 and 2, a fuel supply tank is shown at 10 adapted to contain liquid petroleum gases as a liquid, and particularly butane or propane or any other liquid or material which produces a refrigerating effect when it passes from the liquid to the gaseous state according to the principle for instance governing the operation of the structures of Letters Patent #2,234,900 and #2,244,623 issued to me. The liquid fuel passes by gravity from the tank 10 through a supply pipe 11 through an inlet or expansion valve 12 and under control of the latter through a short pipe 13 into the interior space of a jacket 14, surrounding a cylinder 15 of an internal combustion engine. Of course, the principle may be practiced in connection with an internal combustion engine regardless of the number of cylinders, the single cylinder shown being by way of example only. A piston 16 operates in the cylinder 15 in the conventional manner to operate the engine, and carbureted fuel is adapted to enter the cylinder from a manifold 17 under

control of an inlet valve 18 and exhaust gases pass from the cylinder through a manifold 19 under control of a valve 20.

Valve 12 may or may not be of the expansion type. It has therein a valve member controlling a seat through which the fuel passes and which valve member is operable by a diaphragm controlled by a column of liquid contained in a tube 21 and in a terminally equipped thermostatic bulb 22, the latter being fastened in the jacket of the engine as shown at 23, relatively close to the predetermined level for the liquid fuel as suggested by the dot-dash line at 24. Vapor from the liquid fuel above the level 24, will pass into a pipe or conduit 25, conveying it to the lower end of an expansion valve 26 arranged in communication with the intake manifold 17. Such expansion valve 26 has an air inlet at 27 under control of a valve 28. The inlet of the gas is also under control of a valve 29 located in the mixing valve.

In the operation of the structure, since valve 12 and parts 21—22 are of the thermostatic type used commonly in refrigeration when bulb 24 is chilled, contraction of the liquid contents ensues and the action is transmitted by tube 21 to the bellows-operated valve member within the valve 12 reducing and shutting off the supply of fuel entering the jacket space 14. This action can be so regulated that a certain height or predetermined level of liquid fuel, namely that at 24, can be maintained in the jacket space 14. Such level will leave a vapor space within the space 14 above the fuel so that it may be taken off by pipe 25 and used for fuel purposes. As the gas is drawn off by pipe 25 for use as fuel in the engine, the fuel in the jacket boils or produces more vapor by evaporation as the level of such fuel liquid lowers. The lowering of the liquid opens the valve 12 until the liquid level again raises to the bulb 24 and into contact therewith.

The same results will be accomplished by the use of a float valve as in Figures 3 and 4, which replaces the valve 12 and its thermostatic control. The same parts which are used in Figures 1 and 2, bear the same reference numerals in Figures 3 and 4. In such modified form, an enlargement or chamber 30 is provided on the jacket of the cylinder whose interior provides a float space 31. The chamber 30 at the outer end is closed by a removable plate 32 which mounts a connection consisting of interior and exterior parts 33 and 34, detachably secured together and to the plate by screw threads at 35. A fuel supply pipe 11 connects to the exterior part 34 and within the bore of the part 33, a perforated

valve seat 38 is disposed whose perforation is under control of a needle valve 37. At the inner end needle valve 37 has a block 38 pivoted there-to on a horizontal axis 39, which block in turn is pivoted on a horizontal axis 40 to a lever 41 pivoted on a vertical axis at 42 to a lever 43 which is pivoted on a horizontal axis 44 to the interior part 33. A rod 45 is connected to lever 43 and it carries a float 46 operating in the space 31. The vapor from the fuel in the jacket space 14 above the predetermined level 24 is utilized as exactly in the preceding form of the invention, and as such level 24 recedes the float 46 lowers in order to proportionately retract the valve 37 from its seat 38, permitting additional liquid fuel to enter the space 14 and again raise the float and actuate the part to close the needle valve 37. As the liquid level 24 raises and lowers, the fuel in space 14 will boil to produce the vapor for utilization as fuel, as described with respect to the first form of the invention.

Various changes may be resorted to provided

they fall within the spirit and scope of the invention.

I claim as my invention:

1. A system for cooling an internal combustion engine by means of the fuel, consisting in supplying the fuel in liquid condition into the cooling jacket of the engine, and in passing the fuel as a gas above the liquid level in the jacket, through a mixing valve to a cylinder, and thermostatically controlling the liquid fuel in the jacket at a predetermined level.
2. A system for cooling an internal combustion engine by means of the fuel, consisting in supplying the fuel in liquid condition into the cooling jacket of the engine, and in passing the fuel as a gas above the liquid level in the jacket, through a mixing valve to a cylinder, a valve means controlling the supply of the liquid fuel to the jacket, and thermostatic means to actuate the valve means having the parts disposed in the jacket space approximately at the predetermined level for the liquid fuel.

NELSON M. JONES.
